UNITED STATES PATENT OFFICE

2,066,195

MINING MACHINE

John S. Beltz and Lewis E. Mitchell, Columbus,
Ohio, assignors to The Jeffrey Manufacturing
Company, a corporation of Ohio

Application March 31, 1934, Serial No. 718,452

27 Claims. (Cl. 262—28)

The present invention relates to mining machines of the type adapted to the mining of coal although it should be understood that it may have a general application, and one of the objects 5 of the invention is to provide a mining machine equipped with an elongated cutter-bar which is mounted in heads adapted to be quickly rotated for adjustment to different intersecting planes.

A further object of the invention is to provide improved and efficient adjusting mechanism 10 for effecting movement of the cutter head to various intersecting planes and the locking thereof in adjusted position.

A further object of the invention is the provision of improved and efficient power transmitting mechanism for effecting turning of the cutter head of the kerf cutting mining machine to enable the kerf-cutter to cut either in horizontal planes or in upright planes.

Another object of the invention is the provision of an adjustable pivoted cutter bar in a mining machine providing means for adjusting the elevation and inclination of the cutter head so that such adjustments may be used for effecting feeding movements to cut a parallel ribbed kerf in an upright plane.

More particularly, the object of the invention is to provide in a unitary structure comprising an elongated pivoted cutter bar mechanism for adjusting the elevation and inclination of the cutter head and means for turning the cutter head to position the cutter bar in horizontal or vertical planes and providing mechanism for effecting swinging feeding movement of the cutter bar when in a horizontal plane, said mechanism for adjusting the elevation and inclination being relied on to effect downward feeding movement when the cutter bar is in a vertical plane.

Other objects of the invention will appear 40 hereinafter, the novel features and combinations being set forth in the appended claims.

In the accompanying drawings,

Fig. 1 is a plan view of the track mounted mining machine embodying the present invention;

Fig. 2 is an elevational view of the track mounted mining machine shown in Fig. 1;

Fig. 3 is a sectional elevation taken on the line 3—3 of Fig. 1, looking in the direction of the 50 arrows;

Fig. 4 is a fragmentary sectional view taken on the line 4—4 of Fig. 5, looking in the direction of the arrows;

Fig. 5 is an enlarged plan view of the right 55 hand portion of the structure shown in Fig. 1,

parts being broken away to show certain details of the turnover head mechanism;

Fig. 6 is a sectional view taken on the line 6—6 of Fig. 5, looking in the direction of the arrows;

Fig. 7 is a sectional view taken on the line 7—7 of Fig. 5, looking in the direction of the arrows;

Fig. 8 is an enlarged sectional elevation taken on the line 8—8 of Fig. 1, looking in the direction of the arrows;

Fig. 9 is an enlarged sectional elevation taken on the line 9—9 of Fig. 10, looking in the direction of the arrows;

Fig. 10 is a diagrammatic plan view illustrative of the arrangement of parts mounted on the turntable shown in Fig. 1;

Fig. 11 is an enlarged sectional elevation of the mechanism for rotating the turntable at a feeding speed to effect feeding of the kerf-cutter 20 when in a horizontal plane;

Fig. 12 is an enlarged sectional elevation of the pawl and ratchet mechanism for effecting reversal of the swinging feeding movement of the turntable and the kerf cutting mechanism mounted thereon;

Fig. 13 is an elevational view showing brake mechanism embodied in the construction shown in Fig. 12;

Fig. 14 is a sectional elevation of a portion 30 of the structure shown in Fig. 12;

Fig. 15 is a sectional elevation taken on the line 15—15 of Fig. 12, looking in the direction of the arrows;

Fig. 16 is a bottom plan view of a portion of 35 the frame structure shown in Fig. 1 and the mechanism mounted thereon for securing adjustment in elevation and inclination of the turntable;

Fig. 17 is an enlarged sectional elevation of 40 one of the three adjustable supporting screw posts for the turntable;

Fig. 18 is an enlarged elevational view of the clutch mechanism located at the lower end of each of the adjustable screw posts; and

Figs. 19, 20, and 21 are diagrammatic views illustrating the shearing feeding movements of the machine to effect the cutting of parallel ribbed kerfs in vertical plane.

Referring to Figs. 1 and 2, it will be seen that 50 the supporting frame 22 is mounted on wheels 23, 23 which are adapted to travel on the mine track 24. Mounted on the frame 22 is a supporting ring 25 around which is distributed a series of supporting rollers 26, 26.

55

The ring 25 is mounted for adjustment in elevation and inclination on three upright standards or screw posts 21, 21 at the front end of the frame 22 and on the rear central screw posts 21' at the central portion of the frame 22 as shown in Fig. 1. Each of the screw posts 21, 21, 21' may be the same in construction as that shown in the Levin Patent No. 1,904,489, granted April 18, 1933 for an improvement in coal mining apparatus, and to facilitate explanation of the shearing feeding movements illustrated in Figs. 19 to 21, inclusive, an enlarged sectional elevation of one of such adjustable screw posts is shown in Fig. 17.

Mounted on the ring 25 so as to partake of the 15 adjustments thereof in elevation and inclination is a turntable 28. As shown in Fig. 3 a peripheral flange 29 supports the turntable 28 on the rollers 26. By means of an electric motor 30 connected to mechanism as illustrated in Figs. 8 to 15 inclusive, the turntable 28 may be rotated relatively to the supporting ring 25 and about an upright axis at the center thereof.

On the rear portion of the frame 22 are mounted an additional motor 31 and power transmission mechanism 32 for effecting transportation of the machine along the mine track 24 from place to place in the mine. The power transmission mechanism 32 is also connected to a cable reel 33 on which is wound a cable 34 extending 30 to the source of power for the two electric motors 30 and 31 which are independently operated and controlled.

Fixed rigidly to the turntable 28 and extending radially therefrom is a supporting arm 35 to 35 which is connected a bracket 36, carrying the cutter head 37 to which is secured the elongated cutter bar 38 having an endless chain cutter 39 guided around the periphery thereof. A driving sprocket 40 meshes with the cutter chain and is secured by keys 41 to the lower end of the torque shaft 42 as shown in Fig. 3. On the upper end of the shaft 42 is journaled a bevel gear 43. A clutch 44 is mounted on the shaft 42 for controlling the operation of the sprocket 40, the 45 clutch being operated in turn by a shifter 45 and either of the levers 46 shown in Fig. 5. A plate 47 (Fig. 3) comprising a split ring is secured by cap screws 48 to the cutter bar 38 serves as a 50 guide for the chain 39 during rotation of the sprocket 40.

A guide plate 49 having the shape of a segment of the cylinder may be secured to the hub portion 50 of the cutter bar 38 as shown in Fig. 3.

The hub 50 of the cutter bar is provided with 55 a cylindrical extension 51 which fits into a cylindrical bearing 52 of the cutter head 37. The cylindrical extension 51 and the bearing 52 are concentric with the shaft 42. Also concentric with the shaft 42 is an annular recess 53 on the hub 60 50 in position to fit the annular flange 54 extending from the cutter head 37. By means of cap screws 55, a ring 56 is secured to the periphery of the hub 50 to form an annular groove in which the flange 54 fits. The split ring 56 therefore acts 65 to retain the cutter bar 38 and its hub 50 in engagement with the cutter head 37 while permitting arcuate adjustment of the cutter bar 38.

Extending forwardly from the cutter head 37 is a V-shaped bracket 57 having an opening 70 therethrough for receiving the locking pin 58. The latter may extend into any one of a plurality of openings or recesses 59, 59 in the bracket 60 which is secured to the rear end of the cutter bar 38 as shown in Figs. 3 and 5. After being inserted into one of the openings or recesses 59 the

locking pin 58 may be kept from dropping out by means of a cotter pin 61 as shown in Fig. 3.

As shown in Fig. 3 the armature shaft 62 which projects from the motor 30 in Fig. 1 has secured thereto a bevel pinion 63 which meshes with a 5 horizontal bevel gear 64 secured to the vertical shaft 65. The upper end of shaft 65 is provided with a bevel gear 66 which meshes with the bevel gear 67 mounted on the rear end of the shaft 68, the forward end of the shaft carrying the bevel gear 69 which meshes with the bevel gear 43 on the shaft 42. When the motor 30 is operated the shaft 68 is rotated and when one of the levers 46 is actuated to throw in the clutch 44 power will be transmitted from the shaft 68 to the shaft 42 to 15 rotate the sprocket 40 and thereby drive the endless chain cutter 39 about the periphery of the cutter bar 38.

The details of the turnover head mechanism for rotarily adjusting the plane of the cutter bar 20 on the horizontal axis of the shaft 68 are illustrated in Figs. 3 to 7 inclusive. The cutter head mechanism including the cutter head 37, the hub 50, the shaft 42 and the parts driven thereby, is enclosed in a housing 70 which is provided at its 25 rear end with a tubular extension or neck 71 supported for rotation on the bearing comprising the bushing 72. At the rear end of the neck 71, apparatus is provided for rotarily adjusting the cutter bar from a relatively low horizontal plane to 30 a relatively high horizontal plane and also to vertical or shearing planes on opposite sides of a vertical plane extending through the shaft 68. When the cutter bar is in its high horizontal plane such plane extends above all other parts 35 of the machine while the kerf cutter is in a top-cutting position. By referring to Fig. 5, it will be seen that there is keyed to the hub 73 of the bevel gear 69, a spur gear 74 which meshes with a spur gear 75 keyed to the front end of a shaft 76 40 journaled in the cylindrical bearing 77 which projects rearwardly from the housing 70. At the rear end of the shaft 76 is a pinion 78 (Fig. 6) which meshes with an internal or annular gear 79 integral with the drum 80. The drum 80 as 45 shown in Fig. 3 is journaled on the rotary neck 71 which extends rearwardly from the housing 70. A ring plate 81 fits against an annular shoulder of the neck 71 and at its periphery fits an annular recess in the peripheral portion of the 50 drum 80 to complete the enclosure of the gears 78 and 79. It will thus be seen that when the motor 30 drives the horizontal shaft 68, power is transmitted through the spur gears 74, 75 to the shaft 76 and thence to the gears 78 and 79 to effect 55 rapid rotation of the drum 80. Consequently whenever the motor 30 is operating, the drum 80 is being rotated and this continues so long as the neck 71 is stationary relative to the radial support 36.

In order to effect rotation of the neck 71 and the elongated chain kerf cutter, on the horizontal axis of the shaft 68, friction mechanism in the form of a brake is provided to produce a friction clutch between the gear 79 and the neck 71. 65 This brake mechanism is illustrated in Fig. 6 and comprises operating mechanism mounted on the bracket 82 which is rigidly connected to the stationary retaining plate 83, the latter being detachably secured by means of the bolts 84 to the 70 flange 85 integral with the radial support 36 and extending in a plane at right angles to the shaft 68.

The brake mechanism illustrated in Fig. 6 75 comprises a pair of shoes or brake bands 86, 86

which are adjustably connected at their ends remote from the bracket 82 as illustrated at 87. The brake shoes may be applied to the drum 80 by lifting the lever 88 which is connected by the 5 link 89 to the bracket 90 at 91. It should be understood that the right hand end of the lower section of the brake as viewed in Fig. 6 is rigidly secured to the bracket 90. It will thus be seen, that when the lever 88 is moved up the brake 10 shoes 86, 86 are brought into closer contact with the drum 80 so as to apply the brake, and when the lever 88 is released the spring 92 will effect automatic release of the brake mechanism.

As shown in Fig. 3 an annular groove 93 at the 15 rear portion of the neck 71 is adapted to receive a split retaining ring 94. At the rear end of the neck 71 is located an annular collar 95 which is keyed to the neck 71 by a plurality of keys as shown at 96, 96 in Fig. 4. The collar 95 is bolted 20 to the retaining ring 94 by means of the bolts 97, 97. Therefore, the collar 95 is detachably connected to the rear end of the neck 71.

As above pointed out, the ring 83 is secured to the flange 85 by means of the bolts 84 as shown 25 in Figs. 3, 5, and 6, the retaining plate 83 being cylindrical in shape to afford a housing for the annular collar 95. An inwardly extending flange 98 on the housing 83 serves to retain the neck 71 against outward movement off the bearing 72. 30 That is to say, since the ring 94 fits in the groove 93 of the neck 71 and the ring 94 is secured to the annular collar 95, the flange 98 locks the neck 71 on the bearing 72.

In order to lock the cutter bar 38 for feeding 35 movement in any one of a plurality of intersecting planes of operation, latch mechanism is provided in connection with the peripheral portion of the annular collar 95. As shown in Fig. 7 eight notches 99, 99 are located in the periphery of the 40 collar 95. As shown in Fig. 4 the retaining plate 83 is provided with an outwardly extending bracket 100. On this bracket is pivotally mounted a plate 101 of polygonal or other suitable configuration, which is journaled to the pivotal axis 102. 45 By means of the handle 103 on the plate 101 the latter may be moved from its full line position to its dotted line position shown in Fig. 4.

As shown in Fig. 7 the bracket 100 is provided with a guideway 104 for the spring pressed latch 50 105 which is adapted to fit into any of the notches 99 to lock the collar 95 in adjusted position and therefore lock the cutter bar 38 in its selected plane of operation.

The latch 105 is operatively connected by means 55 of the link 106 to the actuating plate 101. A pin 107 pivotally connects one end of the link 106 to the latch 105 and a pin 108 connects the other end of the link 106 to the operating plate 101. Inside of the bracket 69 is a retaining seat 109 for a spring 110 which extends into a cylindrical recess in the rear end of the latch 105. When the operating plate 101 is moved from its full line position to its dotted line position as shown in Fig. 4 the latch 105 is released from its notch 99 against the action of the spring 110, and when the plate 101 is released the spring 110 urges the latch 105 60 against the peripheral surface of the collar 95 in readiness to automatically snap into the next notch 99.

70 When the latch 105 is released and the brake applied to effect rotary adjustment of the cutter head 37 on the horizontal axis of the shaft 68, the collar 95 as viewed in Fig. 7 should rotate in an anti-clockwise direction so that when the handle 75 103 is released the spring 110 will act to urge the

inner end of the latch 105 along the cut away portions 111, thereby permitting the faces 112 of the notches 99 to act as abutments or limit stops. Therefore, as soon as the neck starts to rotate, the handle 103 of the latch mechanism may be 5 released and the brake held applied with the assurance that the next limit stop 112 will definitely and accurately stop the rotation of the neck at exactly the pre-selected position corresponding to the next notch 99, whereupon the latch will 10 automatically snap into the notch 99 and prevent further rotation of the neck 71. If the brake is held applied after the latch 105 reaches the abutment 112, the drum 80 will slip relatively to the brake shoes. In other words, the brake 15 mechanism will act in the nature of a friction clutch to permit slipping when the rotation of the neck is definitely stopped at a pre-selected position.

In Fig. 7 each notch 99 is spaced 45° from the 20 next adjacent notch. If the cutter bar is in a horizontal plane when the parts are in the position shown in Fig. 7, rotation of the collar 95 so that the latch will be in the next adjacent notch, the cutter bar will occupy a slanting plane at 45° 25 to vertical and horizontal planes extending through the axis of the shaft 68. By proper regulation of the brake mechanism and the timing of the manual release of the latch 105 the cutter bar may be adjusted into slanting planes, 30 vertical planes, horizontal planes and into relatively low and relatively high horizontal planes. If the cutter bar is in a horizontal plane when the parts are in the position shown in Fig. 7, rotation of the collar 95 through an angle of 90° will 35 locate the cutter bar in a vertical plane. When the collar 95 is rotated through an angle of 180° the cutter bar will be inverted. For instance, if the cutter bar is in a relatively low horizontal plane it may be inverted so as to occupy a relatively high horizontal plane, or if the cutter bar 40 is in a shearing position at one side of the machine it may be inverted to occupy a shearing position at the other side of the machine. Of course, when the cutter bar reaches its selected position it is held thereby the latch mechanism 45 against movement in either direction on the axis of the shaft 68. Furthermore, the pin 58 locks the cutter bar against pivotal movement relatively to the cutter head 37 during feeding movement of the kerf-cutter. Consequently when the cutter 50 bar has once been adjusted to its selected position it is held in such adjusted position rigidly connected to the turntable 28 to move bodily therewith.

It should be particularly noted that the turn-over movement on the axis of the shaft 68 from one position to another as permitted by the construction shown in Figs. 4 and 7, is effected at a relatively rapid rate of speed. As above explained, proper timing of the manipulation of the 60 latch 105 by withdrawing the same from its notch and releasing the handle 103 while the brake shoes 86 are applied to the drum 80, will enable the operator to effect a rapid, continuous, rotary movement of the cutter bar through an angle of 65 45° or any multiple thereof. That is to say, he may effect rotation of the cutter bar from one position to another without stopping at each notch 99 but stopping only at the pre-selected notch.

The drum 80 being connected to the shaft 68 as 70 shown in Figs. 3, 5, and 6, the speed of rotation of the pinion 78 as it walks around the stationary annular gear 79 effects a quick rotary adjusting movement of the cutter head 37 and the cutter bar mounted thereon.

During such rotary adjustment of the cutter bar on the axis of the shaft 68 the clutch 46 may be in released position. When the clutch 44 connects the shaft 68 to the sprocket 40 the chain cutter is always driven in the same direction relative to the cutter bar, and therefore it is desirable to control the motor 30 to always rotate in the same direction, but this does not interfere with the desired rotary adjustments of the cutter head on the axis of the shaft 68 because each of such rotary adjustments is made in an anticlockwise direction as viewed in Fig. 7.

As shown in Fig. 3, the radial support 36 is provided with cups or recesses 113 and 114 which always face upwardly and serve to contain lubricant for passage through the holes 115, 116 and 117, 118. The bottom of the recess 113 is provided with an opening 115 which registers with an opening 116 in the bushing 119 for supplying lubricant to the shaft 68. Lubricant from the recess 114 passes along the groove 120 to the bearing bushings 72, 121, and 122.

It will also be seen that when the sections 123 and 124 of the clutch 44 are brought into engagement by actuation of either lever 46 (Fig. 5), the sprocket 40 of the kerf cutter will be rotated. Suitable antifriction bearings are provided for the shaft 33 at 125 and 126. A lubricant seal may be provided at 127 to prevent escape of lubricant from the bearing 126.

The upper bearing 125 may be lubricated after removing the screw plug 128. The cover 129 may be detachably secured to the housing 70 by means of the cap screws 130. By removing the cover 123 the parts shown in Fig. 3 in the housing 70 are rendered accessible for inspection or repairs.

In operation the chain kerf-cutter may cut not only horizontal kerfs throughout a considerable range of elevations, but also vertical kerfs in spaced apart parallel planes. While the provision of eight notches 99 as shown in Fig. 7 affords adjustment of the kerf-cutter into slanting planes extending at 45° to the vertical or horizontal, the kerf-cutter can not be fed transversely of itself when in such slanting plane. However, when the kerf-cutter is in slanting plane it may be sumped into the coal vein by moving the whole machine along the mine track at a feeding speed. For instance, if the shaft 68 is located in a position parallel to the mine track and the cutter bar 38 is adjusted to a position parallel to the axis of the shaft 68, traction feed of the whole machine along the mine track may be relied on to cut a kerf either in a horizontal plane or in a vertical plane or in a slanting plane, having the dimensions of the effective length of the kerf cutter. In other words, a kerf or incision may be cut into the face of the mine vein in any one of a plurality of intersecting planes including horizontal, vertical and slanting planes spaced from the axis of the shaft 68 while the latter is parallel to the mine track.

Inasmuch as those notches 99 which are most frequently used for holding the kerf cutter in horizontal and vertical planes will receive the greatest wear it is desirable to space the cap-screws 97, 45° apart so that the collar may be detached from the retaining ring 94 and reassembled 45° from its worn position, thereby greatly prolonging the life of the notched collar 95. When such readjustment of the collar 95 is made relative to the retaining ring 94 the latter may remain permanently locked to the neck 71 so as to always rotate therewith. It should be understood that whenever the notched collar 95 is se-

cured to the retaining ring 94 it is rigidly connected to the neck 71 to always pivotally rotate therewith. Consequently, when the latch 105 is in one of the notches 99 the cutter bar will be held rigidly against rotation on the axis of the shaft 68 in either direction.

The mechanism for adjusting the elevation and inclination of the turntable 28 and the cutter bar 38 may be substantially the same as that shown in the Levin patents Reissue No. 17,603 granted February 25, 1930 for an improvement in mining machines; No. 1,353,054 granted September 14, 1920 for an improvement in mining machines; and No. 1,904,489, granted April 18, 1933 for an improvement in coal mining apparatus. However, in order to illustrate more clearly the adaptation of such structure to the shearing features illustrated in Figs. 19 to 21 inclusive, which features are embodied in the turnover head mechanism shown in Figs. 3 to 7 inclusive, reference will be made to Figs. 8 to 18, inclusive, before explaining the diagrammatic illustrations in Figs. 19 to 21, inclusive. The mechanism for rotating the turntable 28 is substantially the same as that disclosed and claimed in the application of Nils D. Levin, Serial No. 656,697, filed February 14, 1933.

As shown in Fig. 8 an annular rack 131 is secured to the inner edge of the ring 25. Meshing with the annular gear 131 is a pinion 132 at the lower end of a vertical shaft 133 mounted in the bearing 134 on the turntable 28. Keyed to the upper end of the shaft 133 is a spur gear 135 which meshes with a spur gear 136. By means of the friction disc clutch 137 operated by the sprocket 138 the gear 136 may be connected through the rotating element 139 to the vertical shaft 140. To the lower end of the shaft 140 is keyed a worm gear 141 which meshes with a worm 142 arranged to be driven in one direction or the other by means of the pawl and ratchet mechanism shown in Figs. 11 to 14, inclusive.

As shown in Fig. 9 a manual wheel 143 is mounted on a shaft 144 on the opposite end of which is mounted a bevel gear 145 meshing with a bevel gear 146 mounted for rotation on a vertical axis. A sprocket 147 is connected to the gear 146 to rotate therewith. A sprocket chain 148 connects the sprocket 147 to the sprocket 138. Therefore by rotating the wheel 143 in one direction or the other the friction clutch 137 may be applied or released to effect power transmitting connection between the worm 142 and the annular rack 131.

As shown in Fig. 11, the lower end of the shaft 65 is provided with an eccentric cam 149 on the periphery of which is mounted the eccentric strap 150 to which is pivoted at 151 the reciprocating arm 152. Pivoted at 153 to the upper end of the arm 152 is a bifurcated support 154 carrying the bearing pin 155 as shown in Figs. 11 and 12.

Journalized on the pin 155 and on the shaft 156 are supporting members 157 and 158, and between these members on the pin 155 are reversely arranged pawls 159 and 160. Reversely arranged ratchets 161 and 162 are keyed to the shaft 156 to rotate with the latter. A pawl setting device 163 is provided with openings 164 and 165 in position to permit pawl 166 or pawl 167 to engage its respective ratchet wheel 161 and 162.

By means of the lever 168, the shaft 169 may be rocked in one direction or the other to operate the spur gearing 170, 171 to bring either the opening 164 or the opening 165 into position to permit one pawl 166 or the other pawl 167 to engage its ratchet wheel. A spring pressed pin 172 75

fits into one of the recesses 173 to hold the pawl setting device 163 in adjusted position.

At the right hand end of the shaft 156 as shown in Fig. 12 is secured a brake wheel 174 with which is associated a brake band 175, the latter being held yieldingly applied to the brake wheel 174 by means of the springs 176, 176. During swinging feeding movement in the mine vein vibrations may cause reversal of the worm 142, while the pawl 166 or the pawl 167 is moved from one notch to the next notch. To overcome this tendency of the worm 142 to partially reverse its rotation, the brake mechanism shown at the right hand end of the shaft 156 as viewed in Fig. 12 is relied on to hold the worm 142 in a position to which it has been moved by the pawl and ratchet mechanism.

To facilitate assembly or removal of the pawl and ratchet mechanism for replacement of parts, the bracket 177 for supporting the shaft 156 may be removably secured by means of cap screws 178 to the turntable 28. The bracket 177 may fit into the trough 179 so as to hold in place the sections 180, 180 of the bearing for the right hand portion 25 of the shaft 156.

Spaced at intervals around the peripheral portion of the turntable 28 on the underside thereof are brackets 181 (Fig. 9) in which are mounted fixed vertical bearings 182 for rollers 183 within the rings 184 which are adapted to roll around the inner surface of the ring 25. Lateral thrust on the turntable during swinging feeding movement of the kerf cutter will therefore be taken by the roller bearings 182, 183, 184 to relieve the strain between the pinion 132 and the annular rack 131. It will thus be seen that during swinging feeding movement of the kerf cutter the cutter bar 38 is rigidly connected in adjusted position to the turntable 28 and the latter will be 40 guided concentrically of the stationary ring 27 by means of the roller bearings one of which is shown in Fig. 9, while the power is being transmitted very efficiently from the motor 30 to the pinion 132 to cause the same to travel along the 45 stationary annular rack 131.

The worm gearing 141, 142 shown in Fig. 8 is self-locking, and therefore when the clutch 137 is applied the cutter bar 38 may be held locked in an adjusted position at an acute angle to the 50 mine track. During driving of the chain cutter by means of the motor 30 and the power transmission mechanism between this motor and the chain cutter the pawl setting drum 163 (Fig. 14) may be located in neutral position to hold both 55 of the ratchet pawls 166 and 167 out of engagement with their respective ratchets.

While the cutter bar occupies a horizontal plane which may be located at an acute angle relative to the mine track, the turntable may be 60 locked against rotary movement by means of the latch mechanism at 185 associated with the periphery of the turntable 28 as shown in Fig. 1 and more clearly illustrated in the Levin Reissue Patent No. 17,603, granted February 20, 1930, 65 for an Improvement in mining machines. It will thus be seen that the cutter bar may be adjusted relative to the wheel mounted frame 22 on spaced apart vertical axes when the cutter bar is in a horizontal plane, one vertical axis being in 70 the center of the turntable and the other vertical axis being at the shaft 42 shown in Fig. 3. The pivoted cutter bar 38 is held in adjusted position relative to the radial supports 36 by means of the pin 58, and the turntable is held 75 in adjusted position by the latch mechanism 185.

However, the latch mechanism 185 may be omitted and the pawl lifting drum 128 set at neutral as shown in Fig. 14, so that when the clutch 103 of Fig. 8 is applied, the worm gearing 107, 108 will lock the cutter bar against turning on the axis of the turntable.

The kerf-cutter when in a horizontal plane may be dumped into the coal face extending across the space in advance of the mine track, by traction feed which is effected by a motor 31 operating truck propelling mechanism through the reduction gearing located at 24. Such reduction gearing for effecting movement of the machine along the mine track at a feeding speed may be such as that illustrated in the Levin Patent No. 15,1353,054, granted September 14, 1920 for an Improvement in mining machines.

After the dumping cut has been completed while the kerf cutter is in a horizontal plane, and arcuate feeding movement effected across the working 20 face, the traction feeding mechanism may again be operated to effect a rectilinear withdrawal movement parallel to the mine track, thereby completing the cutting of a parallel ribbed kerf in a horizontal plane. In this manner parallel 25 ribbed kerfs may be cut in relatively narrow entries or in relatively wide entries, the depth of each cut being equal to the full effective length of the cutter bar.

When arcuate feeding movement is effected 30 across the working face in advance of the mine track, it is desirable that the cutter bits on the advance side of the cutter bar shall continuously emerge from the coal face so as to sweep the cuttings therefrom. It is also desirable to reduce 35 the overall height of the mining machine shown in Fig. 2 so that it may operate in relatively low mine chambers or rooms and so that it may be transported along mine entries having low roofs. By reason of the elevating screw mechanism 40 shown in Fig. 17 for the three screw posts distributed as shown at 27, 27, 27' in Fig. 1, the same machine may also be used to cut horizontal kerfs at various elevations while the cutter bar is located in a horizontal plane below a horizontal 45 plane extending through the shaft 68 of Fig. 3. By use of the turnover mechanism shown in Figs. 3 to 7 inclusive the kerf cutter may be located in relatively high horizontal planes above all other parts of the machine. When the cutter bar is 50 inverted however, the arcuate feeding of the cutter bar should be reversed so that the cutter bits will again be on the advance side of the cutter bar in position to emerge from the kerf and sweep the cuttings therefrom. For instance, if the 55 arcuate feeding as viewed in Fig. 1 is anti-clockwise when the cutter bar is in its lower position shown in Fig. 2, the arcuate feed should be clockwise after the cutter bar has been inverted so as to occupy a top cutting horizontal position. It 60 will thus be seen that whether the cutter bar is fed arcuately in a clockwise direction in one plane or fed in an anti-clockwise direction in another plane, the cutter chain will always be kept moving in the same direction so as to emerge from the 65 coal face on the advance side of the cutter bar to effect sweeping of the cuttings from the coal face.

The motor 30 may be continuously operated in the same direction since the cutter chain always travels in the same direction, the reversal of the 70 arcuate feed of the kerf cutter being effected by the reverse feeding mechanism illustrated in Figs. 11, 12, and 14.

Each of the screw posts located at 27, 27, 27' in Fig. 1 includes the construction shown in detail in 75

Fig. 17. These screw posts are connected between the frame 22 and the supporting ring 25 and each screw post comprises compound elevating screw mechanism, a left hand screw element 186 and a right hand screw element 187, the latter being held against rotation at 188. A bracket 189 is secured to the outer face of the ring 25 for supporting the upper screw element 187 and the guide mechanism 190, there being sufficient loose-
 5 ness of fit at 191 to permit inclination of the turntable to secure the steps in the operation during shearing as illustrated in Figs. 19, 20, and 21.
 Fig. 16 is a bottom plan view to show the connection of the driving sprocket chain 192 to the
 10 three separate compound screw elevating devices shown in Fig. 17. The chain 192 is driven from the motor 31 through the reduction gearing 32. Associated with the bottom of each compound screw elevating device is a clutch 193 which when thrown in will rotate the screw element 186 through the fixed nut 194 so as to simultaneously elevate or lower the screw elements 186 and 187. The construction shown in Figs. 16, 17 and 18 is
 15 the same as that shown in the Levin Patent No. 1,904,489, granted April 18, 1933 for an Improvement in coal mining apparatus.

Referring now to Figs. 19, 20, and 21, it will be seen that by manipulating the clutches at the lower ends of the screw posts 27, 27 and 27' the turntable 28 may be tilted to various positions. By keeping the clutch associated with the post 27' released and throwing in the clutches associated with the two front posts, the forward end of the turntable 28 may be elevated to a relatively high position and the cutter bar locked in upwardly extending position by means of the pin 58. That is to say, while the cutter bar is in a horizontal plane it may be easily swung on the shaft 42 as a pivot while the pin 58 is released so that the pin may be inserted in the last hole 59. (Fig. 5.) Then by operating the brake mechanism shown in Fig. 6 and controlling the latch 105 the cutter bar may be rapidly turned through an angle of 90° to a shearing position with the cutter bits arranged to travel at its lower edge from the coal face. While the cutter bar is held rigidly in its adjusted position in a vertical plane with its upper outer end adjacent at the roof of the mine room a sumping feeding movement may be effected by moving the whole machine along the mine track at a feeding speed until the cutter bar reaches the position shown at 195 in Fig. 19. Now upon operating the motor 31 to drive the chain 192 while the clutches associated with the screw posts 27, 27 are applied the compound elevating screw mechanism shown in Fig. 17 may be positively operated to move the kerf cutter downwardly in the direction of the arrow 196 in Fig. 19 until the position of the kerf cutter illustrated at 197 is reached.

The locking pin 58 may then be released and while the clutches for the screw posts 27, 27 are still applied the motor 31 may be reversed to re-elevate the front end of the turntable 28 to the position shown in full lines in Fig. 20. The cutter bar is then locked by means of the locking pin 58 so that it will extend approximately in alignment with the upper surface of the turntable. The motor 31 may then be operated to cause the compound screw mechanism shown in Fig. 17 to positively pull down the kerf cutter from its position shown at 198 to its position shown at 199 in Fig. 20, the feeding movement being in the direction of the arrow 200.

Fig. 21 illustrates the final steps in the cutting of a parallel ribbed kerf in a vertical plane. The front end of the turntable is again in elevated position in Fig. 21 as shown in full lines, and the kerf cutter is locked by means of the pin 58 in the position shown by the dotted lines 201 before the downward feeding movement in the direction of the arrow 202 is begun. Such downward feeding movement to the position illustrated in the dotted lines 203 is effected not only by lowering the front screw posts but also by elevating the rear screw post at 27' until the turntable occupies the dotted line position shown in Fig. 21. When the kerf-cutter occupies the position shown by the dotted lines 203, reverse traction feed of the entire machine is relied on to effect a withdrawal cutting movement in the direction of the arrow 204, thereby completing the cutting of the parallel ribbed kerf which started with the rectilinear sumping feeding movement at the roof as shown in Fig. 1, and was continued by downward feeding movements by means of the compound screw elevating mechanism shown in Fig. 17.

While in Figs. 19, 20, and 21 shearing is illustrated as being carried on from a straight section of mine track it should be understood that by reason of the universal tilting of the turntable and the turning over of the head on the axis of the shaft 68, and releasing the clutch of Fig. 8 while the feed of Fig. 14 is in neutral to permit the turntable to float, the kerf-cutter may be operated efficiently from curved sections of mine track to shear in the rib, for instance in mining operations carried on for the cutting of room necks.

Obviously those skilled in the art may make various changes in the details and arrangement of parts without departing from the spirit and scope of the invention as defined by the claims hereto appended, and we therefore wish not to be restricted to the precise construction herein disclosed.

Having thus described and shown an embodiment of our invention, what we desire to secure by Letters Patent of the United States is:

1. In mining apparatus, the combination with a portable support, of kerf-cutting mechanism mounted thereon, means for adjusting the elevation and inclination of said kerf-cutting mechanism, power operated mechanism for effecting rotary adjustment of said kerf-cutting mechanism on a horizontal axis into intersecting planes, means for automatically stopping rotation of said mechanism in planes 45 degrees apart, and motor operated mechanism for operating said kerf-cutting mechanism in adjusted position including feed thereof.

2. In a mining machine, the combination with a wheeled truck movable along a trackway, of kerf-cutting mechanism mounted thereon and comprising a plane chain kerf cutter, mechanism for adjusting the elevation and inclination of said kerf cutter relative to the horizontal power operated mechanism for effecting rotary adjustment of said kerf cutter on a horizontal axis into a plurality of intersecting planes of operation, means for automatically stopping rotation of said mechanism in planes 90 degrees apart, and motor operated mechanism for operating said kerf-cutting mechanism including the feed of said kerf cutter.

3. A mining machine comprising a cutter bar and a turnover head therefor, means for adjusting said cutter bar to a horizontal plane or a

vertical plane, mechanism comprising a locking element having a plurality of spaced notches in the periphery thereof for holding the cutter bar either in a horizontal plane or a vertical plane, and means for securing said notched locking element in a plurality of adjusted positions so that when in one position one set of notches will be used for holding the cutter bar in the horizontal and vertical planes and when the locking element is adjusted in another position another set of notches will be used for holding the cutter bar in the horizontal and vertical planes.

4. A mining machine comprising an elongated cutter bar and the turnover head therefor, power operated mechanism for moving the cutter head to position the cutter bar in a horizontal plane or in a vertical plane, means comprising a locking element having a plurality of notches in the periphery thereof spaced 45° apart, and means for adjustably securing said locking element in two different positions 45° apart.

5. In a track mounted mining machine, the combination with a wheeled frame adapted to move along a mine track, of a supplemental frame mounted thereon for adjustment relative thereto in elevation and inclination, a turntable mounted on said supplemental frame, kerf-cutting mechanism comprising an elongated cutter bar pivotally connected to a turnover cutter head, means for locking said cutter bar at an adjusted angle relative to said cutter head, power-operated means for rotating said cutter head on an axis extending radially of said turntable, mechanism for automatically stopping and locking said cutter head relative to said turntable with the cutter bar in either a horizontal plane or a vertical plane, means for rotating said turntable to feed said kerf-cutting mechanism while said cutter bar is in a horizontal plane, a plurality of screw elevating devices connected between said wheeled frame and said supplemental frame, operator-controlled power-operated mechanism for positively lifting and lowering and tilting the turntable to effect arcuate shearing feeding movements of the kerf-cutting mechanism while said cutter bar is held in a vertical plane, and means for propelling the whole machine along the mine track at a feeding speed to effect rectilinear sumping and withdrawal feeding movements of the kerf-cutting mechanism either when the cutter bar is in a horizontal plane or when in a vertical plane.

6. In a mining apparatus, the combination with a portable support, a kerf cutting mechanism mounted thereon, power operated mechanism for effecting rotary adjustment of said kerf cutting mechanism on a horizontal axis into intersecting planes, means for automatically stopping rotation of said mechanism in planes 45 degrees apart and maintaining it locked any position where it is stopped, and motor operated mechanism for operating said kerf cutting mechanism in adjusted position.

7. In a mining apparatus, the combination with a portable support, a kerf cutting mechanism mounted thereon, power operated mechanism for effecting rotary adjustment of said kerf cutting mechanism on a horizontal axis into intersecting planes, means for automatically stopping rotation of said mechanism in planes 90 degrees apart and maintaining it locked any position where it is stopped, and motor operated mechanism for operating said kerf cutting mechanism in adjusted position.

8. In a mining apparatus, the combination

with a portable support, a kerf cutting mechanism mounted thereon, power operated mechanism for effecting rotary adjustment of said kerf cutting mechanism on a horizontal axis into intersecting planes, means for automatically stopping rotation of said mechanism in planes 45 degrees apart. 5

9. In a mining apparatus, the combination with a portable support, a kerf cutting mechanism mounted thereon, power operated mechanism for effecting rotary adjustment of said kerf cutting mechanism on a horizontal axis, means for automatically stopping rotation of said mechanism in selected intersecting planes and maintaining it locked in any position where it is stopped, and motor operated mechanism for operating said kerf cutting mechanism in adjusted position. 10

10. In a mining apparatus, the combination with a portable support, a kerf cutting mechanism mounted thereon, power operated mechanism for effecting rotary adjustment of said kerf cutting mechanism on a horizontal axis, means for automatically stopping rotation of said mechanism in selected intersecting planes, and motor operated mechanism for operating said kerf cutting mechanism in adjusted position. 15

11. In a mining machine, the combination with a body, of a kerf cutting mechanism in-

cluding a plane cutter bar and a cutter chain, a cutter bar head pivotally connecting said cutter bar to said body for pivotal movement about an axis substantially parallel with the plane of said cutter bar, a motor driven shaft extending from 35 said body along said axis and into said head for driving said cutter chain, a second shaft, said second shaft being carried in said head on an axis parallel with and spaced from the axis of said motor driven shaft, said shafts being inter- 40 connected, a pinion gear carried by said second shaft, stationary means attached to said body for effecting a driving connection between said gear and said body whereby rotation of said 45 second shaft will produce rotation of said head about its pivotal axis, and means adapted to stop rotation of said head in predetermined intersecting planes. 45

12. In a mining machine, the combination with a body, of a kerf cutting mechanism including a plane cutter bar and a cutter chain, a cutter bar head pivotally connecting said cutter bar to said body for pivotal movement about an axis substantially parallel with the plane of said cutter bar, a motor driven shaft extending from said body along said axis and into said head for driving said cutter chain, a second shaft, said second shaft being carried in said head on an axis parallel with and spaced from the axis of said motor driven shaft, said shafts being intercon- 60 nected, a pinion gear carried by said second shaft, stationary means attached to said body for effecting a driving connection between said gear and said body whereby rotation of said second shaft will produce rotation of said head about its 65 pivotal axis, and means adapted to stop rotation of said head in planes substantially 90 degrees apart. 65

13. In a mining machine, the combination with a body, of a kerf cutting mechanism including a plane cutter bar and a cutter chain, a cutter bar head pivotally connecting said cutter bar to said body for pivotal movement about an axis substantially parallel with the plane of said cutter bar, a motor driven shaft extending from said body 75

along said axis and into said head for driving said cutter chain, a second shaft, said second shaft being carried in said head on an axis parallel with and spaced from the axis of said motor driven shaft, said shafts being interconnected, a pinion gear carried by said second shaft, stationary means attached to said body for effecting a driving connection between said gear and said body whereby rotation of said second shaft will produce rotation of said head about its pivotal axis, and means adapted to stop rotation of said head in planes substantially 45 degrees apart.

14. In a mining machine, the combination with
a body, of a kerf cutting mechanism including
15 a plane cutter bar and a cutter chain, a cutter
bar head pivotally connecting said cutter bar to
said body for pivotal movement about an axis
substantially parallel with the plane of said cutter
bar, a motor driven shaft extending from
20 said body along said axis and into said head for
driving said cutter chain, a second shaft, said
second shaft being carried in said head on an
axis parallel with and spaced from the axis of
said motor driven shaft, said shafts being inter-
25 connected, a pinion gear carried by said second
shaft, stationary means attached to said body
for effecting a driving connection between said
gear and said body whereby rotation of said sec-
ond shaft will produce rotation of said head
30 about its pivotal axis, and means adapted to stop
rotation of said head in a substantially vertical
plane.

plane.

15. In a mining machine, the combination with a body, of a kerf cutting mechanism including a plane cutter bar and a cutter chain, a cutter bar head pivotally connecting said cutter bar to said body for pivotal movement about an axis substantially parallel with the plane of said cutter bar, a motor driven shaft extending from said body along said axis and into said head for driving said cutter chain, a second shaft, said second shaft being carried in said head on an axis parallel with and spaced from the axis of said motor driven shaft, said shafts being interconnected, a pinion gear carried by said second shaft, stationary means attached to said body for effecting a driving connection between said gear and said body whereby rotation of said second shaft will produce rotation of said head about its pivotal axis, and means adapted to stop rotation of said head in predetermined intersecting planes, said last named means comprising a notched ring attached to said head for rotation therewith, a spring-pressed latch carried by said body and adapted to ride on said ring and snap into a notch when said latch is opposite said notch.

16. In a mining machine, the combination with a body, of a kerf cutting mechanism including a plane cutter bar and a cutter chain, a cutter bar head pivotally connecting said cutter bar to said body for pivotal movement about an axis substantially parallel with the plane of said cutter bar, a motor driven shaft extending from said body along said axis and into said head for driving said cutter chain, a second shaft, said second shaft being carried in said head on an axis parallel with and spaced from the axis of said motor driven shaft, said shafts being interconnected, a pinion gear carried by said second shaft, stationary means attached to said body for effecting a driving connection between said gear and said body whereby rotation of said second shaft will produce rotation of said head about its pivotal axis, and means adapted to stop rotation of said head in predetermined intersect-

ing planes, said last named means comprising a notched ring having notches spaced substantially 90 degrees apart and attached to said head for rotation therewith, a spring-pressed latch carried by said body adapted to ride on said ring and snap into a notch when said latch is opposite said notch. 5

17. In a mining machine, the combination with
a body, of a kerf cutting mechanism including
a plane cutter bar and a cutter chain, a cutter
bar head pivotally connecting said cutter bar to
said body for pivotal movement about an axis
substantially parallel with the plane of said cutter
bar, a motor driven shaft extending from said
body along said axis and into said head for driv-
ing said cutter chain, a second shaft, said second
shaft being carried in said head on an axis parallel
with and spaced from the axis of said motor
driven shaft, said shafts being interconnected,
a pinion gear carried by said second shaft, sta-
tionary means attached to said body for effect-
ing a driving connection between said gear and
said body whereby rotation of said second shaft
will produce rotation of said head about its piv-
otal axis, and means adapted to stop rotation of
said head in predetermined intersecting planes,
said last named means comprising a notched
ring having notches spaced substantially 45 de-
grees apart and attached to said head for rota-
tion therewith, a spring-pressed latch carried by
said body adapted to ride on said ring and snap
into a notch when said latch is opposite said
notch.

18. In a mining machine, the combination with 35
a body, of a kerf cutting mechanism including
a plane cutter bar and a cutter chain, a cutter
bar head pivotally connecting said cutter bar
and said body for pivotal movement about an axis
substantially parallel with the plane of said cutter
bar, a motor, driving connections between 40
said motor and said cutter chain for driving said
cutter chain, means for rotating said head about
its axis comprising means for effecting an im-
positive connection between said motor and said
head, and means operating automatically to stop 45
rotation of said head in predetermined positions,
said stop means comprising a notched ring hav-
ing more than two peripheral notches and at-
tached to said head for rotation therewith, a
spring-pressed latch carried by said body and 50
adapted to ride on said ring and snap into a
notch therein when said latch is opposite said
notch.

19. In a mining machine, the combination with
a body, of a kerf cutting mechanism including
a plane cutter bar and a cutter chain, a cutter
bar head pivotally connecting said cutter bar
and said body for pivotal movement about an axis
substantially parallel with the plane of said cutter
bar, a motor, driving connections between said
motor and said cutter chain for driving said cutter
chain, means for rotating said head about its
axis comprising means for effecting an imposi-
tive connection between said motor and said head,
and means operating automatically to stop ro-
tation of said head in predetermined positions,
said stop means comprising a notched ring hav-
ing notches spaced substantially 90 degrees apart
and attached to said head for rotation therewith,
a spring-pressed latch carried by said body and
adapted to ride on said ring and snap into a
notch therein when said latch is opposite said
notch. 55

20. In a mining machine, the combination with a body, of a kerf cutting mechanism including 75

5 a plane cutter bar and a cutter chain, a cutter bar head pivotally connecting said cutter bar and said body for pivotal movement about an axis substantially parallel with the plane of said cutter bar, a motor, driving connections between said motor and said cutter chain for driving said cutter chain, means for rotating said head about its axis comprising means for effecting an im-
 10 positive connection between said motor and said head, and means operating automatically to stop rotation of said head in predetermined positions, said stop means comprising a notched ring having notches spaced substantially 45 degrees apart and attached to said head for rotation therewith, a spring-pressed latch carried by said body and adapted to ride on said ring and snap into a notch therein when said latch is opposite said notch.

21. In a mining machine, the combination with 20 a supporting frame, of a motor mounted thereon, a chain kerf-cutter comprising a cutter bar, mechanism for supporting said cutter bar on said frame for adjustment to any one of a plurality of intersecting planes on a longitudinal forwardly 25 extending axis, means comprising a shaft for driving said chain kerf-cutter from said motor, mechanism driven from said shaft for rotatably adjusting the cutter bar on said longitudinal axis comprising a gear rotatable with respect to said frame, and means yieldable upon over-load for selectively holding the gear in fixed relation to said frame to cause power from said shaft to effect adjustment of the cutter bar to a selected plane.

35 22. In a track-mounted mining machine, the combination with a wheeled truck movable along a trackway, of supporting framework mounted thereon, cutting mechanism comprising a cutter bar having a cutter chain adapted to cut a kerf in the coal face when the cutter bar is presented edgewise thereto, a motor, mechanism driven by said motor for operating said cutting mechanism including the driving of said cutter chain and the swinging of said cutter bar in its own plane, 40 supporting connections between said cutter bar and said supporting framework for permitting adjustment of said cutter bar to various intersecting planes including horizontal and vertical planes, mechanism for effecting rotary adjustment of the cutter bar to such intersecting planes, said mechanism comprising a gear meshing with a pinion and yieldable and releasable means for securing the gear against rotation to cause the pinion to travel around the gear and effect the 45 turning-over movement of the cutter bar to a selected plane, and mechanism for locking the cutter bar in the plane to which adjusted.

23. In a mining machine, the combination with 50 a support, of a kerf cutting mechanism mounted thereon for adjustment about a longitudinal axis, power operated mechanism for effecting

5 rotary adjustment of said kerf cutting mechanism on said longitudinal axis, means for automatically stopping rotation of said kerf cutting mechanism in selected intersecting planes 90 degrees apart and maintaining it locked in any 10 position where it is stopped, and motor operated mechanism for operating said kerf cutting mechanism in any adjusted position.

24. In a mining machine, the combination with 10 a support, of a kerf cutting mechanism mounted thereon for adjustment about a longitudinal axis, power operated mechanism for effecting rotary adjustment of said kerf cutting mechanism on said longitudinal axis, means for automatically stopping rotation of said kerf cutting mechanism in selected intersecting planes and maintaining it locked in any position where it is stopped, and motor operated mechanism for operating said kerf cutting mechanism in any adjusted position.

25. In a mining machine, the combination with 15 a support, of a kerf cutting mechanism mounted thereon for adjustment about a longitudinal axis, power operated mechanism for effecting rotary adjustment of said kerf cutting mechanism on said longitudinal axis, means for automatically stopping rotation of said kerf cutting mechanism in selected intersecting planes 45 degrees apart and maintaining it locked in any 20 position where it is stopped, and motor operated mechanism for operating said kerf cutting mechanism in any adjusted position.

26. In a mining machine, the combination with 25 a support, of a kerf cutting mechanism mounted thereon for adjustment about a longitudinal axis, means including a friction brake for effecting rotary adjustment of said kerf cutting mechanism on said longitudinal axis, means for automatically stopping rotation of said mechanism in selected intersecting planes and maintaining 30 it locked in any position where it is stopped, and motor operated mechanism for operating said kerf cutting mechanism in any adjusted position.

27. In a mining machine, the combination with 35 a body, of a kerf cutting mechanism including a plane cutter bar and a cutter chain, a cutter bar head for carrying said cutter bar, said head being connected to said body for pivotal movement about a longitudinal axis, a motor, driving connections between said motor and said cutter chain for driving the latter, means for rotating said head about its axis comprising a friction brake cooperating with a rotating ring gear which when operated effects a driving connection between 40 said motor and said head, and means operating automatically to stop rotation of said head in intersecting planes.
